UNITED STATES PATENT OFFICE

150,736

DESIGN FOR AN AIRPLANE

Frederick I. Steele, Columbus, Ohio, assignor to
Curtiss-Wright Corporation, a corporation of
Delaware

Application July 26, 1946, Serial No. 131,977

Term of patent 7 years

(Cl. D71—1)

To all whom it may concern:

Be it known that I, Frederick I. Steele, citizen of the United States, residing in Columbus, in the county of Franklin and the State of Ohio, have invented a new, original, and ornamental Design for Airplanes, of which the following is a specification, reference being had to the accompanying drawing, forming a part thereof.

Figure 1 is a top plan view of an airplane, showing my new design;

Figures 2 and 3 are front and side elevations, respectively, wherein the airplane is shown in flight attitude and the landing gear extended is represented by the dotted portion extending below the main body of the airplane.

Figure 4 is a view from the rear and to the side of the longitudinal axis of the airplane with said airplane in flight attitude.

The characteristic features of my design re-

side in the portions shown by means of full lines in the drawing.

I claim:

The ornamental design for an airplane, as shown and described.

FREDERICK I. STEELE.
